CIRCUIT BREAKER

Lawrence M. Persons, St. Louis, Mo., assignor,
by mesne assignments, to Automatic Control
Corporation, St. Louis, Mo., a corporation of
Delaware

Application December 16, 1936, Serial No. 116,131

9 Claims. (Cl. 200—122)

The present invention relates generally to protective devices and more particularly to a thermally-actuable circuit breaker which includes a snap make-and-break action and mechanism adapted to automatically reset the contacts in make relation after a separation thereof.

An object of the present invention is to provide a thermally-actuable circuit breaker which is adapted to interrupt the electrical circuit of an energy-translating device upon excessive current therethrough or upon a dangerous internal overheating of the device.

Another object is to provide a thermally-actuable circuit breaker which includes means for automatically resetting the device subsequent to a current interruption action thereof.

Another object is to provide a thermally-actuable circuit breaker which includes a heating element adapted to actuate the circuit breaker by current passing therethrough.

Another object is to provide a thermally-actuable circuit breaker which includes mechanism for closing and opening the contacts thereof with a snap to prevent arcing.

Another object is to provide an electrical contact which is movable relative to its support.

Another object is to provide a snap break action for a circuit breaker which includes means that effects movement of one contact relative to its support during said action.

Another object is to provide a thermally-actuable circuit breaker which is adapted to efficiently and effectively protect an energy-translating device, as a motor, under a variety of conditions.

Another object is to provide a thermally-actuable circuit breaker which is compact in structure, cheap to manufacture and adapted in all respects to fulfil all the purposes and advantages sought therefor.

Other objects and advantages will appear from the following description, taken in conjunction with the accompanying drawing, in which:

Fig. 1 is a plan view of a thermally-actuable circuit breaker constructed in line with the present invention.

Fig. 2 is a side elevation of the circuit breaker shown in Fig. 1.

Fig. 3 is a section on the line 3—3 of Fig. 1, showing the contacts in make relation.

Fig. 4 is a section on the line 3—3 of Fig. 2, showing the contacts in break relation.

Fig. 5 is a side elevation of the side of the circuit breaker opposite from that shown in Fig. 2.

Fig. 6 is a section on the line 6—6 of Fig. 2.

Fig. 7 is a section on the line 7—7 of Fig. 3.

Fig. 8 is a section on the line 8—8 of Fig. 4.

Fig. 9 is a perspective of one type of bowed spring member employed in the present device.

Fig. 10 is a perspective of one of the contacts and its support.

Referring to the drawing more particularly by reference numerals, 15 indicates generally a circuit breaker constructed in line with one embodiment of the present invention, and includes a base 16 of insulative material. A U-shaped support generally indicated 17 is fixed to the base 16 in inverted position, the bight 18 of the U being spaced from the said base 16 by substantially 10 vertically disposed legs or walls 19 and 20. Each of the legs includes a projection 21 which extends through the base 6 (Fig. 7) and is peened over against a backing plate 22 that is contiguous to the base 16 against the surface opposite to that 15 supporting the legs 19 and 20. A firm anchorage is thus established for the support 17. Each of the legs 19 and 20 further has a V-shaped notch 23 and an opening 24 two sides of which define a V 25 oppositely disposed to and slightly 20 above the V-notch 23. The bight 18 includes a marginal recess 26 and a projection 29 which is offset as at 30 from the plane of the bight proper.

A substantially rectangular element or member generally designated 31 has a central portion cut out, as is indicated at 32. The element 31 is adapted to be slipped over the support 17 and is supported thereby with one wall or pivot edge 33 resting in the V-notches 23 for pivotal movement thereabout as a transverse axis. The element 31 includes longitudinal flanges 34 for strengthening purposes and a transverse flange 35 across that end remote from the pivot edge 33. A flat spring 43 is fixed to the member 31 at 43' and supports at its free end a contact 42, which includes an enlarged head 42'. The contact 42 extends through a hole 44 in the member 31 so that the head 42' is located in the assemblage beneath the member 31. The hole 44 is of a diameter intermediate the diameter of the neck 40 of the contact 42 and the head 42' to prevent inadvertent withdrawal of the head 42' through the hole 44. The spring 43 is biased towards the member 31 so that the head 42' at all times has a force tending to push it downwardly (Fig. 45) from the member 31. Such a movable contact prevents arcing. Of course, the contact may be fixed directly to the member 31, or otherwise spring influenced relative thereto, if preferred.

A flexible member 36 of substantially rectangular configuration, which includes a longitudinal projection 37 at one end and two lateral projections 38 at the other end, is disposed with the projection 37 extending through a slot 41 in the flange 35 of the element 31 and the projections 38 in the V's 25. Shoulders 39 adjacent the projection 37 abut the inner face of the flange 35. The distance between the inner face of the flange 35 and the V's 25 is less than the distance be- 60

tween the shoulders 39 and edges 40 of the projections 38 so that the member 36 is maintained under bowed compression.

A J-shaped fabricated bimetallic member generally designated 45 includes a first section 46 which defines the shape of the member and serves as a base to which a second section 47 of U-shape is welded. Obviously, a conventional construction may be used, if preferred. The section 46 terminates in a return bend 50 to provide a guide and support for a screw 51 that extends through threaded apertures 52 and 53 in the section 46 proper and in the return bend 50, respectively. The member 45 is connected to the projection 29 of the support 17 at 55 by welding, bradding, or the like. The member 45 and the support 17 are disposed through their connection 55 so that the long side of the J extends back over the support 17 to locate the screw 51 with its joint 54 above the member 31 just outwardly of the pivot line 33, whereby the screw 51 is adapted to pivot the member 31 about its pivotal support in a manner to be described.

A U-shaped member generally designated 57 (Fig. 10) includes legs 58 and 59 and a bight 60, which is bent at substantially right angles to the legs 58 and 59 at 61 and 62. The leg 58 includes apertures 63 and 64 while the leg 59 carries a contact 65. The member 57 is fixed to the base 16 by means of brads 66 which extend through the apertures 63 and 64. The member 57 is disposed so that the contact 65 lies directly beneath the contact 42 for cooperative make-and-break action therewith. The leg 59 is bent relative to the bight 60 and the leg 58 so that, when the member 57 is in place on the base, the contact 65 is spaced from the said base 16 and is adapted to yield through its inherent resiliency when the contact 42 comes into make relation therewith. The contact 65 may be mounted in fixed relation to the base 16, if preferred. Where the contact 42 is of the double movement type disclosed, the contact 65 is often fixed to the base 16.

A heater element 70 of a generally sinuous outline is disposed adjacent the section 46 of the bimetallic member 45, and is connected at one end to a terminal 71 fixed to said member 45 and at the other end to a terminal 72, which is supported by the base 16. A lead 73 is connected to the terminal 72. A lead 74 is connected to one of the brads 66 and a lead 75 is connected to the backing plate 22. The circuit breaker is, of course, constructed of well known materials suitable for the various elements.

55

Operation

The thermally-actuatable circuit breaker just described is adapted to be used with energy-translating devices generally for protective purposes, but it is particularly useful in conjunction with a motor. In practice, the circuit breaker is disposed within a casing of a motor in a position to receive substantially the full effect of heat given forth by the motor windings. Hence, it is adapted to function to interrupt the supply of current to the motor, either from ambient heat within the motor casing passing from the motor windings caused from a continuous small overload, or the like, or from heat generated by the heater element effected by a short circuit or stoppage which would cause excessive current to pass through the heater element as well as through the windings.

When the circuit breaker is installed within a motor casing and the leads are properly hooked

into the motor circuit in a manner desired, the elements of the circuit breaker will be disposed as is shown in Fig. 3, wherein the contacts 42 and 65 are in engagement, and the screw 51 is disposed with its point 54 spaced from the member 31. The bowed flexible member 36 is disposed with the pivot line established by the V's 25 above a line drawn through the pivot line 33 and the abutments 39, so that the bowed member tends to bias the contact 42 into a closed relation with the contact 65. In other words, the bowed member 36 tends to pivot the member 31 in a clockwise direction about the pivot line 33 (Fig. 3).

When heat from whatever source reaches the bimetallic member 45 and is increased to an effective value, stresses will be set up therein of a well-known nature, and the screw 51 will be moved downwardly towards the member 31. In its continued downward movement, due to a continued increase in temperature, the point 54 of the screw 51 will engage the member 31 and pivot it about the pivot line 33 against the action of the flexible member 36. During the small initial movement of the member 31 while the force transmitted through the screw point is building up sufficiently to overcome the effect of the spring 36 and the inertia of the elements, the contact 65 will follow the contact 42, maintaining an engagement therewith due to the resiliency of its supporting member 57. The lever arm between the point 54 and the pivot line 33 is only a small fraction of the lever arm between the pivot line 33 and the abutments 39, and the vertical travel of the point 54 is a proportionately small fraction of the vertical travel of the abutment 39. The contact 42 is moved away from the contact 65 with a snap action once the inertia of the elements is overcome.

The movement of the members 31 a predetermined distance upwardly before the contact head 42' is withdrawn upwardly cooperates with the upward spring of the contact 65 to assure a snap separation of the contacts, which prevents arcing and its resultant destruction of the contacts. Counterclockwise or upward movement (Fig. 3) of the member 31 is stopped when the flange 35 comes into contact with the bimetallic member. Obviously, when the contacts are snapped apart, the current to the motor, or other device protected, is interrupted and damage from heat is prevented.

As the heat about the circuit breaker is dissipated, the bimetallic member 46 moves back to its normal position, carrying with it the screw 51. The pressure on the member 31 is relieved, whereupon the flexible member 36 becomes effective to snap the contacts 42 and 65 into engaging relation. The circuit breaker is then in operative condition and is again ready to protect the motor, or other device, upon which it may be installed.

It is clear that there has been provided a thermally-actuatable circuit breaker which is adapted to fulfill all of the objects and advantages sought. It is to be understood that the above description and the accompanying drawing have been given by way of example and illustration and not by way of limitation, the invention being limited only by the following claims.

What is claimed is:

1. A circuit breaker comprising a base, a support fixed to said base, a member pivotally mounted on said support having contact means, a resilient member having a fixed connection with the pivoted member and pivotal connection

- with the support, said contact carrying member and said resilient member cooperating to maintain both members in respective pivotal relation on the support, second contact means disposed to cooperate with said first contact means, and cooperatively disposed thermally-actuable means adapted to move said pivoted member to break the contacts.
2. A thermally-actuable circuit breaker comprising a base, a U-shaped support fixed to said base having the bight thereof spaced therefrom by legs in the form of walls, a V-notch in each wall, an aperture having a V as a part of the outline in each wall, a contact-carrying member surrounding the support and pivoted thereto in the apices of the V-shaped notches, a resilient member having a fixed connection with the contact-carrying member and a pivotal connection with the support in the apices of the V-shaped portions of the apertures, second contact means connected to the base and disposed to cooperate with the first contact means, and a thermally-responsive member fixed to the support and disposed to move the contact-carrying member upon increase in heat to break the contacts.
3. A circuit breaker comprising a base, a U-shaped support fixed to said base with the bight spaced therefrom, a member having contact means pivotally mounted on said support, said member being maintained in its pivotal relation to the support by a resilient member having a fixed connection with the pivoted member and pivotal connection with the support, second contact means disposed to cooperate with said first contact means, thermally-actuable means connected to said support adapted to move said pivoted member to break the contacts, and a heater element disposed adjacent the bimetallic member.
4. A circuit breaker comprising a base, a support including two substantially vertical walls fixed to said base, spaced opposed V-shaped notches in each of said walls, a contact-carrying member surrounding said support and pivotally engaging in one set of V-notches, a resilient member having one end pivotally engaging said other set of notches and having the other end fixed to said contact-carrying member at the end remote from the pivotal connection of said contact-carrying member, a second contact fixed to the base and disposed to cooperate with said first contact, and thermally-actuable means fixed to said support and adapted to move said contact-carrying member to withdraw said first contact from said second contact, said break being effected with a snap.
5. A circuit breaker comprising a base, a support including two substantially vertical walls fixed to said base, spaced opposed V-shaped notches in each of said walls, a contact-carrying member surrounding said support and pivotally engaging in one set of V-notches, a resilient member having one end pivotally engaging said other set of notches and having the other end fixed to said contact-carrying member at the end remote from the pivotal connection of said contact-carrying member, a second contact fixed to the base and disposed to cooperate with said first contact, thermally-actuable means fixed to said support and adapted to move said contact-carrying member to withdraw said first contact from said second contact, said break being effected with a snap, and a heater element connected to said bimetallic element and disposed adjacent thereto.
6. A thermally-actuable circuit breaker comprising a base, a U-shaped support fixed to said base having the bight thereof spaced therefrom by legs in the form of walls, a V-notch in each wall, an aperture having a V as a part of the outline in each wall, a contact-carrying member surrounding the support and pivoted thereto in the apices of the V-shaped notches, a resilient member having a fixed connection with the contact-carrying member and a pivotal connection with the support in the apices of the V-shaped portions of the apertures, said resilient member being of greater length than the straight line distance between its connections, a line through the apices of the V-notches being closer to the base than a line through the apices of the V-portions of the apertures and said fixed connection between the contact-carrying member and the resilient member being below a line drawn through the apices of the V's in one wall, second contact means connected to the base and disposed to cooperate with the first contact means, and a thermally-responsive member fixed to the support and disposed to move the contact-carrying member upon increase in heat to break the contacts.
7. A circuit breaker comprising a base, a U-shaped support fixed to said base with the bight spaced therefrom, a member pivotally mounted on said support having contact means, a resilient member having a fixed connection with the pivoted member and pivotal connection with the support maintaining said member in its pivotal relation to the support, second contact means disposed to cooperate with said first contact means, and operating means connected to said support adapted to move said pivoted member to break the contacts.
8. A circuit breaker comprising a base, a support fixed to said base, a member having contact means pivotally mounted on said support, said member being maintained in its pivotal relation to the support by a resilient member having a fixed connection with the pivoted member and pivotal connection with the support, second contact means disposed to cooperate with said first contact means, and means connected to said support adapted to move said pivoted member to break the contacts.
9. A circuit breaker comprising a base, a U-shaped support fixed to said base having the bight thereof spaced therefrom by legs in the form of walls, a V-notch in each wall, an aperture having a V as a part of the outline in each wall, a contact-carrying member surrounding the support and pivoted thereto in the apices of the V-shaped notches, a resilient member having a fixed connection with the contact-carrying member and a pivotal connection with the support in the apices of the V-shaped portions of the apertures, said resilient member being of greater length than the straight line distance between its connections, a line through the apices of the V-notches being closer to the base than a line through the apices of the V-portions of the apertures and said fixed connection between the contact-carrying member and the resilient member being below a line drawn through the apices of the V's in one wall, second contact means connected to the base and disposed to cooperate with the first contact means, and a member fixed to the support and disposed to move the contact-carrying member to break the contacts.
